UNITED STATES PATENT OFFICE.

LUTHER L. BEVIS, OF FRANKLIN, GEORGIA.

PLANTER.

1,142,481.

Specification of Letters Patent.

Patented June 8, 1915.

Application filed August 14, 1914. Serial No. 856,791.

To all whom it may concern:

Be it known that I, LUTHER L. BEVIS, a citizen of the United States, residing at Franklin, in the county of Heard and State 5 of Georgia, have invented a new and useful Planter, of which the following is a specification.

This invention relates to planters having means whereby either cotton seed or grain 10 can be deposited, one of the objects of the invention being to provide novel means under the control of the supporting wheel whereby agitating and ejecting mechanisms will be operated.

15 A further object is to provide actuating mechanism which can be shifted readily into and out of operative relation with the wheel, thus to control the operation of the ejecting mechanism.

20 Another object is to provide ejecting mechanism which can be controlled readily to regulate the amount of seeds discharged.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, can be made within the scope of what is claimed, without departing from the spirit of the invention.

In the accompanying drawings the preferred forms of the invention have been 35 shown.

In said drawings:—Figure 1 is a side elevation of the planter. Fig. 2 is a plan view thereof. Fig. 3 is a central vertical longitudinal section through the lower portion 40 of the hopper and the ejecting and agitating mechanism. Fig. 4 is a section on line A—B Fig. 3. Fig. 5 is a perspective view of the seed trough inverted. Fig. 6 is a view similar to Fig. 3, but showing a modified structure for use in planting grain. Fig. 7 is a perspective view of the trough used 45 in connection with said modifications, the trough being inverted. Fig. 8 is a perspective view of a portion of the seed carrier or slide. Fig. 9 is an enlarged section on line C—D Fig. 8. Fig. 10 is a perspective view of a covering wheel which can be used in connection with the planter. Fig. 11 is a

longitudinal section through a modified form of ejecting means which may be used 55 in lieu of the brush shown in Fig. 6.

Referring to the figures by characters of reference; 1 designates side strips suitably connected at their rear ends, as shown at 2 and supporting a hopper 3 provided in its 60 bottom with a longitudinal slot or outlet 4. Slidably mounted upon the bottom of the hopper so as to overhang the side portions of the opening 4 are plates 5 which, by being adjusted toward or from each other, regulate 65 the width of the opening. Handles 6 may be connected to the sides of the hopper and extending forwardly from the side strips 1 are straps 7 to which a clevis 8 is connected.

A shaft 9 is journaled within the side 70 strips 1 near the front ends thereof and is supported by a wheel 10. A gear 11 rotates with the shaft close to one of the side strips 1 and secured to said side strip and adjacent the gear 11 are upper and lower guides 12 75 between which a frame 13 is slidably mounted, these guides being so shaped as to hold the frame against displacement relative thereto. A shaft 14 is journaled in the frame and carries a gear 15 and this shaft 80 is provided with a crank arm 16 to which is connected a pitman 17. A holding pin 18 is extended downwardly through the guides 12 and the frame 13 and serves to hold the frame against sliding movement upon the 85 guides.

Secured to one of the side strips 1 is a guide plate 18' having a longitudinal slot 19 and slidably mounted in this slot is a laterally extending arm 20 secured to a stem 21. 90 This stem projects rearwardly from a cylindrical plunger 22 and the rear portion of the stem is guided within a plate 23 upstanding from the rear connection 2. Plunger 22 is adapted to reciprocate within 95 a trough 24 which is provided along its sides with longitudinal flanges 25. These flanges extend over and are supported by plates 26 secured to the bottom of the hopper 3, it thus being possible to slide the 100 trough longitudinally upon the plates 26 so as to bring its forward end to any desired position relative to the opening 4.

The rear end portion of the trough 24 is provided in its bottom with slots 27 and secured within the trough so as to overhang

the slotted portion of the bottom is a shield 28 designed to fit snugly around the top portion of the plunger 22 and to extend upwardly from the trough, as shown. One of the flanges 25 is provided in its rear end portion with openings 29 and any one of these openings is adapted to receive a bolt 30 slidably mounted on the back portion of the hopper 3. Thus the trough can be held 10 in any position to which it may be adjusted longitudinally relative to the hopper.

An apron 31 hangs downwardly from the front portion of the hopper and in front of the trough 24, this apron constituting deflecting means whereby seeds ejected from the trough by the plunger are prevented from being thrown onto the wheel 10.

A transverse shaft 32 is journaled within the hopper above the opening 4 and this shaft is provided at one end with a sprocket 33 receiving motion, through a chain 34, from a sprocket 35 secured to the axle 9. Shaft 32 is provided, directly over the opening 4, with a star wheel 36 constituting means for forcing seeds downwardly into the opening 4. Secured to the shaft 32 close to each side of the hopper 3 are agitating fingers 37, these fingers being preferably extended inwardly from the walls of the 30 hopper and toward the star wheel as shown particularly in Figs. 2 and 4.

Covering shovels 38 may be attached to the rear portions of the side strips 2 or, if preferred, these shovels may be disconnected 35 from their standards 39 and a cross shaft 40 may be secured to the standards, this shaft carrying a covering wheel 41, as shown in Fig. 10.

Before using the machine the trough 24 is adjusted longitudinally so that its front 40 end will be any desired distance from the apron 31. The plates 5 are also adjusted toward each other so as to produce an outlet opening 4 of the desired width. The pin 45 18 is then removed and frame 13 adjusted longitudinally until the gear 15 is brought into mesh with gear 11. Pin 18 is then reinserted into the guides 12 and the frame 13 after which the machine is moved forward. During the forward motion of the machine, the rotating wheel 10 and axle 9 will cause motion to be transmitted through the sprocket 35, chain 34 and sprocket 33, to the shaft 32 so that the star wheel 36 and the agitating fingers 37 will be set in motion. At the same time gear 11 will rotate the gear 15 and will cause the pitman 17 to reciprocate arm 20 and plunger 22. During each forward stroke of the plunger 50 all of the seeds which may have been deposited in the trough 24 in front of the plunger will be ejected forwardly from the trough and against the apron 31 from which they will fall onto the ground. The openings 27 in the trough prevent any trash or

other objectionable substances accumulating in the trough where it might interfere with the proper operation of the plunger.

By removing gear 15 from its shaft 14 and substituting a larger or smaller gear, 70 the distances between the hills can be increased or diminished.

The mechanism hereinbefore described is especially designed for use in planting cotton seed. Should it be desired to use the 75 machine for planting grain, a trough such as shown in Fig. 7 would be substituted for the trough 24. This trough shown in Fig. 7 is angular in cross sectional contour and has an outlet opening 42 in the bottom thereof adjacent its forward end. In other respects the trough is the same as that heretofore described. A slide 43 is used in connection with this trough and has a laterally extending arm 44 adapted to be actuated by 85 the pitman 17. This slide 43 is provided with an opening 44' the diameter of which can be reduced by inserting a ring 45, as shown particularly in Fig. 9. The slide 43 is adapted to work under a brush 46 secured 90 to the front portion of the hopper 3 and extending into the front portion of the trough. A guard plate 47 is secured within the rear portion of the trough and fits closely upon the slide 43 so as to prevent the escape of 95 seed rearwardly from the trough.

The operation of this modified form is similar to that heretofore described, the forward movement of the machine resulting in the reciprocation of the slide 43 and as this 100 slide is brought to position under the outlet opening 4, certain of the seeds will be deposited within the opening 44' and conveyed forwardly to a point above the opening 42 and under the brush 46.

If desired the trough can be entirely removed from either of the structures shown and the contents of the hopper 3 thus be allowed to fall directly from the hopper to the ground. Under these conditions the 110 plunger 22 or the slide 43 are dispensed with, the pitman 17 being disconnected from the crank 16 and the frame 13 shifted longitudinally so as to bring its gear 15 out of mesh with the gear 11.

Instead of using a brush for the purpose of ejecting grain from the machine, a structure such as shown in Fig. 11 may be used. This structure includes an arm 48 adapted to be secured to the front wall of the hopper and having a rearwardly extending channel 49 under which the slide 43 is adapted to work. In this channel is pivotally mounted a scraper 50 the rear or active edge of which is normally pressed against the slide 43 by a spring 57 mounted on a bracket 52. An ejector 53 is pivotally mounted in the channel and has a lug 54 adapted to press down into the opening in the slide, there being a spring 55 bearing downwardly on the ejector. 130

Thus it will be seen that as the slide carries grain forwardly, the scraper 50 will press back any surplus grain while the lug 54 will spring downwardly into the opening in the 5 slide and eject the grain therefrom.

What is claimed is:—

1. A planter including a hopper having an outlet, a supporting wheel, a gear revoluble with the supporting wheel, a frame adjustable toward and from the gear, a gear revoluble within the frame and movable into and out of mesh with the first named gear, a seed receiving trough adjustably mounted under the hopper for receiving seeds from 10 the outlet, a member mounted for reciprocation within the trough, and means operated by the gear on the frame for reciprocating said member.
2. The combination with a hopper having 20 a seed outlet, of a trough slidably mounted under the outlet and supported by the hopper, means depending from the hopper and adjacent the front end of the trough for limiting the forward movement of the seeds 25 within the trough, a seed conveying member slidably mounted within the trough, a supporting wheel, and means operated by the supporting wheel for reciprocating said member.
3. In a planter, the combination with a 30 hopper having an outlet, of a trough adjustably connected to the bottom of the hopper and extending under the outlet, means for holding said trough against longitudinal movement, means depending from the front portion of the hopper and into the path of the seeds within the trough, a member slidably mounted in the trough for shifting the seeds longitudinally thereof, a guard secured

within the trough and fitting snugly upon 40 said member, a supporting wheel, means actuated thereby for reciprocating the member.

4. A planter including a hopper having an outlet, agitating means within the hopper, a supporting wheel, means operated thereby for actuating said agitating means, a trough supported by and extending under the hopper, said trough being adjustable longitudinally, means upon the hopper and 45 trough for holding said trough against movement relative to the hopper, an ejecting member slidably mounted within the trough, means operated by the supporting wheel for reciprocating said member, and 50 means connected to the front portion of the hopper for engaging seeds projected forwardly by said member.

5. In a planter the combination with a 55 hopper having an outlet in the bottom thereof, of a trough adjustably connected to and supported by the hopper, means upon the hopper for engaging the trough to hold it against longitudinal movement, there being outlet openings in the rear portion of the 60 bottom of the trough, a plunger slidably mounted within the trough, a deflecting 65 apron depending from the hopper and adjacent the front end of the trough, a supporting wheel, and means operated by said 70 wheel for reciprocating the plunger.

In testimony that I claim the foregoing as my own, I have hereto affixed my signature in the presence of two witnesses.
